SOUNDING TOY

Henry Singer, Honolulu, Territory of Hawaii

Application October 28, 1948, Serial No. 57,112

1 Claim. (Cl. 46—177)

1

This invention relates to a toy pistol, and more particularly to a toy pistol provided with a musical bell.

The object of this invention is to provide a toy pistol which, when "fired," rings a bell in lieu of detonating a cap or discharging a missile.

Another object of the invention is to provide a toy pistol which has attached thereto a pair of bells that are adapted to be rung selectively to produce a series of musical sounds.

A further object of the invention is to provide a toy pistol which is extremely simple and inexpensive to manufacture.

Other objects and advantages will be apparent during the course of the following description.

In the accompanying drawings forming a part of this application, and in which like numerals are employed to designate like parts throughout the same:

Figure 1 is a side elevational view of the toy pistol with parts thereof broken away;

Figure 2 is a sectional view taken on the line 2—2 of Figure 1;

Figure 3 is an enlarged sectional view taken on the line 3—3 of Figure 1;

Figure 4 is an enlarged sectional view taken on the line 4—4 of Figure 1.

Referring in detail to the drawings, the numeral 10 designates a solid body having the configuration of a gun or pistol and includes a handle 11. The body 10 is provided with a cut-out 12 on the right side thereof and communicating with the cut-out 12 is a groove 13 for a purpose to be subsequently described. Arranged adjacent the cut-out 12 is a bell 14 which is secured to the body 10 by a screw 15 which projects from a lug 16 that is secured to the body 10. The screw 15 projects through an aperture 17 in the bell 14 and a nut 18 releasably locks the bell thereon. For sounding or ringing the bell 14, a tapper is arranged therein and the tapper comprises a bent bar 19 having a ball 20 secured to its upper end. A link 21 extends through the groove 13, and a pin 25 which is pivotally connected to body 10 connects the other end of the bar 19 to a finger-engaging ring 34 arranged below the body 10.

A second cut-out 22 is formed in the opposite or left side of the body 10 and arranged adjacent thereto is a different-sized bell 23 which is secured to the body 10 in the same manner that the other bell is secured thereto. For ringing the bell 23, a tapper is provided and comprises

2

an L-shaped bar 24 having a ball 26 on its upper end. The other end of the bar 24 is pivotally connected to the body 10 by a pin 27 and is mounted for movement in a recess 28 which communicates with the cut-out 22. A link 29 is arranged on the left side of the body 10 and is secured to the pin 27, there being a knurled thumb-engaging tab 30 secured to the link 29. A stop member 31 limits movement of the ball 26 away from the bell 23.

In use, the handle 11 is gripped and the tab 30 tapped downwardly with the thumb to cause the ball 26 to ring the bell 23 and the index finger is used to pull the ring 34 backwardly to cause the ball 20 to strike the bell 14. The bar 19 then drops back and rests on the lug 16 until it is again raised. The ring 34 is large enough to permit a push-pull action by the user's fingers and is large enough to provide play therein.

As many embodiments may be made of this inventive concept, and as many modifications may be made in the embodiment hereinbefore shown and described, it is to be understood that all matter herein is to be interpreted merely as illustrative and not in a limiting sense.

I claim:

In a sounding toy, a solid body shaped in the configuration of a cap pistol, said body having a circular recess formed in a side thereof, a stud projecting outwardly from the center of said recess, a bell mounted on said stud and overlying the recess, a trigger disposed below said body in the plane of its longitudinal center, said recess having a slot opening downwardly through its side wall, an angled arm offset laterally from said trigger and extending upwardly through said slot, a pivot pin mounted in the bottom wall of said recess and engaged by the free end of said arm, and a tapper extending from the free end of said arm adjacent the point of pivot thereof to strike the bell whenever the trigger is actuated.

HENRY SINGER.
